(57) **CLAIM**

The ornamental design for a paintbrush holder, as shown and described.

DESCRIPTION

FIG. 1 is a top front perspective view of a paintbrush holder showing my new design;

FIG. 2 is a bottom rear perspective view thereof;

FIG. 3 is a front elevational view thereof;

FIG. 4 is a rear elevational view thereof;

FIG. 5 is right-side elevational view thereof;

FIG. 6 is a left-side elevational view thereof;

FIG. 7 is a top plan view thereof;

FIG. 8 is a bottom plan view thereof;

FIG. 9 is a top front perspective view of a flattened configuration of the present invention;

FIG. 10 is a front elevational view thereof;

FIG. 11 is a rear elevational view thereof;

FIG. 12 is right-side elevational view thereof;

FIG. 13 is a left-side elevational view thereof;

FIG. 14 is a top plan view thereof; and,

FIG. 15 is a bottom plan view thereof.

The evenly spaced dashed lines showing in FIGS. 9-11 represent creases and form no part of the claimed design. The remaining broken lines showing of a hook and loop fastener in FIGS. 9-15 are included for the purpose of showing portions of the paintbrush holder that form no part of the claimed design.
